AUTOMATIC RADIO PROGRAM SELECTOR

Gordon R. Pennington, Bloomfield Hills, Mich.

Application May 25, 1942, Serial No. 444,331

17 Claims. (Cl. 200—37)

1

This invention relates to automatic program selectors for radio receiving sets.

The primary object of my invention is to provide an improved radio program pre-selector, the user of which can pre-select any one of up to seven radio transmitting stations (or, if preferred, no reception at all) for each of the 511 fifteen minute periods between 6 A. M. through 12:15 P. M., or any other desired portion of the day, from Monday morning to Sunday midnight, and have these pre-selected stations automatically tuned in on his or her radio set at the times desired, week after week, until different pre-selections are made.

A further object of my invention is to provide a fully automatic program selector, as above, which will include a minimum number of wires and, therefore, a minimum number of wire connections.

A further object of my invention is to provide in such a selector, means for quickly and easily setting, or changing, the pre-selections.

A further object of my invention is to provide the minimum interval between the tuning out of one station and the tuning in of another when shifts are called for.

A still further object of my invention is to provide, in such a selector, precise timing of the tuning-in of the programs pre-selected even though the dimensions of the time controlling switch parts are not held to close manufacturing tolerances.

Other objects will be apparent from the following description and drawings, in which:

Fig. 1 is a view of the side of a conventional radio cabinet showing my preferred location of the face of my novel selector in such a cabinet.

Fig. 2 is a face view of that part of my invention, in its preferred form, which is visible from the exterior of the radio cabinet.

Fig. 3 is a partial section along the line 3—3 in Fig. 2.

Fig. 4 is a partial section along the line 4—4 in Fig. 2.

Fig. 5 is a fragmentary rear view of the device.

Fig. 6 is a fragmentary section through the line 6—6 of Fig. 5.

Fig. 7 is a fragmentary view from the plane 7—7 in Fig. 6.

Fig. 8 is a fragmentary section along the line 8—8 in Fig. 7.

Fig. 9 is a fragmentary section along the line 9—9 in Fig. 7.

Fig. 10 is a fragmentary view along the line 10—10 in Fig. 5.

2

Fig. 11 is an end view from the plane 11—11 in Fig. 5.

Fig. 12 is an interrupted diagram illustrating the cycle of events and their timing during each 5 24 hour period.

Fig. 13 is a fragmentary view of the frontal face of an alternative form of my invention.

Fig. 14 is a partial section on the line 14—14 in Fig. 13.

Fig. 15 is a partial section on the line 15—15 in Fig. 14.

Fig. 16 is a developed view of the cylindrical surface shown in Fig. 14, and showing the contact areas on the wall of the hole and on the plug.

In general, my novel automatic radio program selector comprises a laminated panel, consisting of several brass sheets (one for each of the radio broadcasting stations from among whose programs selection is to be offered) cemented between sheets of plastic or other (relatively) non-conducting material and pierced by seven groups of holes (one group for each day in the week and one hole in each group for each fifteen minute broadcasting period during that part of

25 the day for which automatic selection is to be offered) and electrically conducting plugs manually insertable, or rotatable, in any or all of said holes each adapted to selectively contact any one of said brass sheets and thereby to pre-select,

30 for the periods corresponding to said holes, any one of the tuning circuits of an associated conventional "push-button" radio receiving set. Electric clock driven switching mechanism of novel design completes electrical circuits, at the

35 proper times, through said plugs and therefore, through the particular brass sheet each of said plugs has been pre-disposed to select. Each of said circuits can be adapted by relays, or other well known electric means, to supplant or operate

40 conventional "push-button" tuning circuits or other tuning devices in the associated radio receiving set.

My novel program selector can be marketed as a separate unit adapted to be hooked up by 45 any radio service man to any existing "push-button" receiving set but I prefer to describe it as built into the same cabinet as the receiving set it is to control.

In the form of my invention shown in Figs. 1 50 to 12, inclusive, the panel 20 is built up of the plastic face 21 and plastic sheets 22, 23, 24, 25, 26, 27, 28 and 29 alternating with, and cemented to, thin sheets 30 to 36, inclusive, of conducting metal such as hard copper or brass. Panel 20 55 is pierced by fourteen horizontal rows of holes

37, two rows for each day of the week as labelled by the letters 38 molded on the plastic face 21. One hole in each pair of rows corresponds to each fifteen minute period of the day, as identified by the figures 39 molded along the top of face 21.

The metal sheets 30 to 36, inclusive, are provided at one end with projecting tabs 40 to 46, inclusive, to which are soldered wires 50 to 56, inclusive, which complete circuits paralleling and, when the set is on automatic selection, replacing, the usual push button circuits (not shown) of the associated conventional radio receiving set in cabinet 19.

In a receptacle (not shown) located in any convenient part of the radio cabinet 19, are kept a quantity of each of seven similar, but different, station pre-selecting switch plugs 60 to 66, inclusive (of which 60, 65, 66 alone are shown). Plugs 60, identified by a letter A, 70, stamped or etched on their ends, are provided with flexible metallic fingers 67, attached by rivets 68 to hold these plugs in place, when inserted in holes 37 against the shoulders 12, and with flexible metallic fingers 77 attached by rivets 78 so located as to make electrical contact with the metal sheet 30 which serves to complete the circuit for tuning in transmitting station A. Plugs 61, 62, 63, 64, 65 and 66 are identical except that they are respectively identified by letters B, C, D, etc. (71 to 76 inclusive) and, upon them the fingers 77 are located so as to contact respectively the metal sheets 31 to 36, inclusive, which complete the tuning circuits for stations B, C, D, etc. Which of these plugs 60 to 66, inclusive, is inserted in any hole 37 determines which of the stations A to G, inclusive, will be automatically tuned in on the day of the week, and the period of the day, to which that hole corresponds.

The identical tips 69 of all of the plugs 60 to 66, inclusive, form contact points which project beyond the plastic sheet 29 when the plugs are fully inserted in any of the holes 37. These tips 69 are contacted by the metallic fingers 80 to 86 or 90 to 96, inclusive, as the contact carrier 87 moves across the back face of the panel 20.

The contact carrier 87 is provided with a follower 88 which engages the continuous double spiral groove 89 in the shaft 97. The spindle portion 98 of the follower 88 is journaled in the needle bearing 99. A screw plug 100 prevents the parts 98 and 99 from getting out of place.

The shaft 97 is fixed by means of the screw 104 to the cam disc 103 which is keyed to the shaft 102 of the 24 hour electric clock 101 which is held by screw 107 to the bracket 105 on the frame 113. By appropriate gearing, the shaft 102 revolves once every half hour in a clockwise direction when viewed as in Fig. 11.

The groove 89 has a left hand lead per turn equal to the center to center distances between the holes in any horizontal row. At each end it reverses in a half turn. The return, or right hand spiral, has such a lead, and number of turns, as to move the carrier 87 through a complete cycle back and forth in 48 turns or 24 hours.

When the associated radio receiving set is dialed to be in automatic selection, current is led to the selector mechanism through wire 108 which is soldered to connector 109 which is held by nut 110 and stud 111 in electrical contact with the spring-brass finger 112 which tends to press against the frame 113, away from the contact 114. Whenever the carrier 87 moves to the right hand end of its travel (between 5:45 and

6:00 A. M.) the boss 115 on the carrier 87 pushes the screw 116 to the right, thus forcing the bar 117 against the spring 112 which is bent into the position 112' touching the contact 114 and continuing the electrical circuit through connector 118 and wire 119 to the "mercoid" switch 120. The bar 117 is held in its extreme right hand position by the detent spring 121 which engages notch 122 in bar 117 until, as the carrier 87 reaches the left hand end of its travel (between 12:15 and 12:30 P. M.) the boss 123 pushes the screw 124 to the left, moving the bar 117 back into the position shown in Fig. 5 and thus allowing the spring 112 to leave contact 114 and thus make the selector inactive during the hours between about 12:20 P. M. and 5:50 A. M. while the carrier 87 returns from left to right.

The wire 119, after entering the "mercoid" switch 120, divides into two branches 121 and 122 which approach, but do not quite touch, the contacts 123 and 124. The mercoid switch 120 is clipped to the bar 129 which pivots on the pin 132 in the bracket 133 fixed to the frame 113. A roller 127, mounted on pin 128 fixed to the bar 129, is held in contact with the periphery of the cam disc 103 by the spring 130. When the roller 128 is in contact with the portion 103a of the periphery, the bar 129 tilts to the left (in Fig. 11) and the mercury drop or globule 131 consequently rolls to the left and completes the circuit through contact 123 and wire 125. When the roller 128 is in contact with the other half 103b of the periphery, the tilt is to the right and the drop 131 completes the circuit through contact 124 and wire 126. As disc 103 revolves a half revolution in fifteen minutes, the wires 125 and 126 are alternately energized for fifteen minute periods. The interval between the instant when the mercury drop 131 breaks the contact on one end and the instant when it makes contact at the other end of the switch is very brief. (As will be shown later, this is the interval between the tuning out of one station at the end of each fifteen minute period and the tuning in of another station, or the retuning in of the same station, and will be negligible.)

Wire 126 connects electrically with the brass commutator ring 134 through the connector 135, the brush holder 136, the spring 137, and the carbon brush 138. The wire 125 connects electrically with the brass commutator ring 139 through the connector 140, the screw 141, and the flexible brass finger 142. The commutator rings 134 and 139 are riveted to the Bakelite disc 143 which is riveted to the shaft 144 which is fixed to the ratchet wheel 145 by the pin 146. The ratchet wheel 145 is yieldingly held in one of seven positions (one for each day of the week) by the spring steel retainer 147 which is fixed to the carrier 87 by the screw 148. Each time the carrier 87 moves to the left hand end of its travel, the ratchet tooth 145a which is lowest is engaged by the bar 149 which can oscillate on the screw 150 fixed in the frame 113 but is normally held against the stop 151 by the spring 152. Slightly after 12:15 P. M. (the exact moment being determined by the adjusted length of the bar 149) the ratchet wheel 145 is revolved 51 $\frac{1}{4}$ degrees counterclockwise (as viewed in Fig. 5) by the bar 149, and is maintained in the new position for the succeeding twenty-four hours by the retainer 147.

At each of the positions taken by the ratchet wheel 145, the projection 153 on the commutator ring 139 is in contact with one of the spring brass contactors 80 to 86, inclusive, and the projection

154 on the commutator ring 134 is in contact with that one of the spring brass contactors 90 to 96, inclusive, whose reference number ends in the same digit. When the switch is in the position shown in Fig. 7 (which is the Wednesday position) contactor 82 becomes energized when wire 125 is energized and contactor 92 becomes energized when wire 126 is energized. Thus, the contactor which moves over the upper row of holes, i. e., the holes for the even hours and half hours for any day of the week, is energized for fifteen minutes and then the contactor which moves over the lower row of holes for the same day of the week is energized. The area of the contactor tips which bear on the ends 69 of such plugs 60 to 66, inclusive, as may have been inserted in their path may be such as to make electrical contact simultaneously with plugs in consecutive holes in any row and plugs may be contacted simultaneously in different rows. However, only that one of the contactors which is in contact with a plug in the hole for a given fifteen minute period will be energized. By adjusting the relative positions of the electric clock 101, the cam disc 103, and the shaft 97, the shift-over from energizing plugs in consecutive time positions as indicated on the face of the panel 20 can be synchronized precisely with the hands of the electric clock and, if the latter is set to the correct time, with the program changes in the transmitting radio stations. The day of the week position of the ratchet wheel 145 can be synchronized either by running the clock ahead the necessary number of 12 hour periods or by manually rotating the ratchet wheel. A button and manually operating ratchet bar (not shown) can be provided to make the day of the week adjustment convenient. Optionally, also, lights can be located to shine on, or through, the designations for the days of the week, using conventional means (not shown) to visually indicate the day of the week.

The diagram, Fig. 12, shows the daily cycle of operation of the set. Following this around clockwise, the solid black rectangles show the periods during which plugs in successive holes are energized and the stations corresponding to the letter designations 70 to 76, inclusive, on the plugs are tuned in. At point 153, or at about 6:37½ A. M., the plug in the 6:45 A. M. hole (in any given row) is contacted by one of the contactors 90 to 96 (according to the day of the week). This 6:45 A. M. plug is not, however, energized until precisely 6:45 A. M. when the mercury switch cuts out the contactors 80 to 86 and cuts in the contactors 90 to 96. The plug in the 6:45 A. M. hole remains in contact with its contactor until about 7:12½ A. M. when the contactor moves on to contact the plug (if any) inserted in the 7:15 hole. However, the 6:45 plug ceases to be energized after 7:00 A. M. when the mercury switch shifts the connection to the upper row of holes in the pair of rows for the day in question. Similarly, such plugs as may have been inserted in consecutive holes (alternately in upper and lower rows corresponding to the day of the week in question) are energized and the metal sheets 30 to 36, inclusive, energized selectively according to the plug designations pre-selected and inserted in these holes. As each of the sheets 30 to 36, inclusive, completes a circuit controlling the associated radio receiving set which tunes in a particular frequency and therefore, normally, a particular station, the programs desired can be

preselected for each of the broadcasting periods of the week and will be tuned in automatically (provided the set is on automatic selection) at the precise proper times, week after week, until new pre-selections are made.

At the point 155, or about 12:20 P. M. the bar 117 will be shifted away from the spring 112 which thereupon will break contact with the part 114 and thus prevent the tuning in of all stations until point 156, or about 5:50 A. M., when the bar 117 is shifted so as to bring the spring 112 again in contact with the part 114 thus re-energizing the selecting mechanism. The clock 101 in the meantime continuously receives current, independently, by wires (not shown) connected to the usual house lighting circuit so that the movement of the carrier 87 is normally continuous.

The normal manner of use of this device is as follows: After the owner has set the electric clock 101 to the correct hour and the ratchet wheel 145 to the correct day of the week (if the optional indicating lights are provided this adjustment will, of course, be visual, otherwise the day of the week can be determined by seeing into which hole, under the proper hour designation, the insertion or removal of a plug will tune the set on or off). If then the user, for example, desires to have his radio set automatically tuned in Mondays, Wednesdays and Fridays on a program broadcast by station A (as identified by a list made up by the service man who may have tuned his various push button choices) at eight P. M., he selects, from the receptacles provided for the purpose in the cabinet 19, three plugs 60 marked A, and inserts these in the holes under 8 P. M. in the Monday, Wednesday, and Friday rows. Thereafter, so long as the radio set and the selector mechanism continue in operation, the pre-selected stations will be tuned in at the selected time, week after week, until the plugs are removed. As program changes are announced by the transmitting stations, or as the user's choice alters, he has but to remove the plugs no longer suitable and insert others as desired. It is expected that the average user will need to make only a few changes, if any, per week normally.

When no plug is inserted in any particular hole, no station will be tuned in during the period corresponding. Although I have shown my design as giving seven station choices, it will be apparent that by merely increasing the number of metallic sheets in the panel and the number of plug variations to correspond, selection could be made from any number of stations.

Figs. 13, 14, 15 and 16 illustrate an alternate form of my invention insofar as this is not identical to the construction already described. In general, this alternate construction differs from the first form in that the station selecting plugs are not removable but can be rotated, preferably by a key, into any one of eight angular positions to pre-select any one of seven stations, or no station at all, at the time corresponding to the plug position. This necessarily requires a full set of 511 plugs but offers the advantage that it can be reset to new program selections in few seconds and there are no loose plugs that can be lost.

The plugs 200, which are all alike, have screw machine heads 201 on the sides of which are formed flats 202. A key 203 fits over the round portions of the heads 201 and has a flat surface to engage the flats 202. This key can be conveniently attached by a light chain (not shown) to the cabinet 19 and kept, when not in use, in a receptacle at the base of the panel 20. When this

key 203 engages any one of the plug heads 201 and is rotated so that the arrow 204 points in any one of the positions shown in the rosette 205, the plug 200 will (as will be shown) be set to complete the electrical circuit through the brass sheet of sheets 230 to 236 which is correlated with the tuning circuit in the associated radio set for the transmitting station whose call letters correspond to the identifying letters 206 placed (by any convenient conventional method) opposite seven of the rosette points. When the arrow 204 is turned to point vertically upwards, there will be no contact with any of the brass sheets in the panel 20 and therefore no program will be tuned in at the quarter hour corresponding to the plug position.

A thin walled brass tube 207, which has been tinned on the outside, is pressed into the plug head 201 and fixed thereto by a soldering operation. A spiral ridge 208 is raised .007" to .010" on all except the ends of the tube 207 by a radial coining operation, or otherwise. The helix angle of this ridge is such as to produce a quarter of a revolution of the ridge around the plug in the distance between the centers of any two of the brass sheets 230 to 236, inclusive. It will be noted from Figure 14 that the spiral 208 is of such a length as to enable selective contact of the sheets 230-236 during a revolution of the plug. Preferably this length will, as in the preferred embodiment, be approximately 1½ turns such having the advantage that any plane passed through the axis of the spiral will intersect the latter at three points in contact with the wall of the hole 237 so as to obtain good electrical contact at the time the spiral 208 engages one of the sheets, this being facilitated by the slight distortion of the plug to which reference is hereinafter made. Although I do not desire to be precise as to this number of turns it will be manifest that when less than the full 1½ turns is used the advantageous three point contact will be lost in some planes and when 1½ turns is much exceeded there will be more than three points of contact in some planes resulting in unnecessary thickness, and therefore cost, of the panel 20.

Five hundred and eleven (511) holes 237, which are circular except for radially inwardly projecting tabs 238 (22½° from the vertical) are punched in each of the brass sheets 230 to 233, inclusive, before these are cemented between the plastic sheets 222 to 229. Holes 239 with radially inwardly projecting tabs 240, an equal amount from the vertical in the opposite direction, are similarly punched in the brass sheets 234, 235 and 236. When the holes 241 are drilled through the cemented panel these are so located, and of such a diameter, as to cut off portions 242 and 243 of the tabs 238 and 240, respectively, but not otherwise to contact the brass sheets 230 to 236, leaving a clearance 244 (which may or may not become fully filled with plastic during the cementing operation) between the surface of the drilled hole and the brass except where the tabs 238 and 240 are located, thus providing electrical contact surfaces 250 to 256, inclusive, at, and only at, the tab locations. The amount of space so provided is preset to be sufficient to allow for expected variations in hole locations in production. Likewise the tabs 238 and 240 are made of sufficient length to assure that they will be trimmed during the drilling operation to form the contact areas 250 to 256, inclusive, on the surface of the hole.

A plug 200 is shown in Figs. 14, 15 and 16 in the position in which it contacts the brass sheet 230 through the contact area 250. If this plug

be turned 45° counterclockwise (as seen from the front of the panel) the raised ridge 208 will contact the brass sheet 234 through the contact area 254. Further rotation in the same direction will establish contacts, at 45° intervals, with the brass sheets 231, 235, 232, 236 and 233 in succession through the contact areas 251, 255, 252, 256 and 253. An additional 45° of rotation in the same direction (or 45° of clockwise rotation from the position shown) will establish no contact and is, therefore the "off" position. I prefer to proportion the width of the top, or contacting portion, of the ridge 208 and the widths of the tabs, and therefore of the contacting areas 250 to 256, inclusive, so that, as the plug 200 is rotated, each contact will be made at approximately the point when the preceding contact is broken. Thus it will not be necessary for the user to position the plugs accurately when station selections are made, as angular positions merely approximating those indicated on the rosette 205 will produce the desired result.

The flats 202 must, of course, be accurately positioned, angularly with respect to the spiral 208. This positioning can readily be accomplished in an automatic machine by machining the flat while the assembly of the head 201 and the tube 207 (soldered at an earlier position) is gripped in the die which forms the ridge 208. This die is machined so as to make the top of the ridge 208 project a few thousandths of an inch outside of the cylinder which would just fit easily into the drilled hole 241 and which substantially coincides with the cylindrical surfaces 207^a and 207^b at the ends of the tube 207. Thus, when a plug 200 is inserted in a hole 241, the tube 207 is necessarily distorted slightly. This distortion, in combination with the resiliency of the hard drawn brass of which the tube 207 is made, assures positive pressure between the top of the ridge 208 and the contact areas 250 to 256, inclusive, which are flush with the walls of the drilled holes 241. After the plugs 200 have been inserted in the holes 241, brass caps 259 are firmly pressed on the cylindrical end portions 207^b of the plugs 200 to hold the latter in place and to provide contact with the contactors 89 to 86 or 90 to 96, according to location.

The operation of this alternate form of my invention is the same as for the form first described, except as indicated above.

To either form of my invention, conventional relay circuits may be added, if desired, to cut off the flow of current through the tubes of the associated radio receiving set when none of the tuning circuits through the panel 20 are energized.

Numerous other modifications of the invention will be apparent to those skilled in the art from the teaching herein and it is not intended to limit the spirit or scope thereof except as set forth in the claims appended below. The terms "horizontal" and "vertical" are used herein to conveniently describe relative orientation but it will be obvious that the structure described can readily be built to function properly in any attitude.

I claim:

1. In an automatic radio program selector, the combination of: a panel pierced by seven groups of holes and consisting of a plurality of metallic elements, each presenting a contact surface within in each of said holes, sandwiched between layers of electrically non-conducting material; markings relating each of said holes to a particular broadcasting period of the day and each of said groups of holes to a particular day of the week;

plugs operable in said holes to make electrical contact with any one of said elements; a contact carrier provided with contacts adapted to make electrical connections with said plugs; electric clock driven means adapted to move said contact carrier across said panel to make the said connections during the periods of each day corresponding to said markings; switching means, correlated to said electric clock driven means, adapted to complete circuits, on each day of the week, through, and only through, such of said plugs as are in the group of holes corresponding to that day of the week; and switching means adapted to break said circuits during that portion of the day not covered by said markings.

2. In an automatic radio program selector, the combination of: a panel pierced by seven groups of holes and consisting of a plurality of metallic elements, each forming part of an electrical circuit adapted to tune an associated radio receiving set to a particular broadcasting station and each presenting a contact surface within each of said holes, sandwiched between layers of electrically non-conducting material; markings relating each of said holes to a particular broadcasting period of the day and each of said groups of holes to a particular day of the week; plugs operable in said holes to make electrical contact with any one of said elements; a contact carrier provided with contacts adapted to make electrical connections with said plugs; electric clock driven means adapted to move said contact carrier across said panel to make the said connections during the periods of each day corresponding to said markings; switching means correlated to said electric clock driven means, adapted to complete circuits, on each day of the week, through, and only through, such of said plugs as are in the group of holes corresponding to that day of the week; and switching means adapted to break said circuits during that portion of the day not covered by said markings.

3. In an automatic radio program selector, the combination of: a panel consisting of a plurality of sheets of electrically conducting material cemented between sheets of relatively non-conducting material; a plurality of holes through said panel arranged in seven pairs of rows; markings relating each of said pairs of rows to a particular day of the week and each of said holes to a particular broadcasting period of the day; plugs operable in said holes to make electrical contact with any one of said sheets of conducting material; a contact carrier provided with fourteen contacts so located as to maintain electrical connections simultaneously with all of said plugs in holes corresponding to the same broadcasting period of the day; electric clock driven means adapted to move said contact carrier across said panel to maintain said connections for periods exceeding and including the broadcasting periods corresponding to said markings; similarly driven switching means adapted to energize, on each day of the week, the said plugs, and only the said plugs, in the pair of rows corresponding to that day of the week; and similarly driven switching means adapted to energize each of said plugs only during a period approximating the broadcasting period corresponding to the hole in which such plugs are located.

4. In an automatic radio program selector, the combination of: a panel consisting of a plurality of metal sheets cemented between plastic sheets; a plurality of holes through said panel arranged in seven pairs of alternately staggered rows; ex-

teriorly visible markings relating each of said pairs of rows to a particular day of the week and each of said holes to a particular broadcasting period of the day; plugs operable in said holes to make electrical contact with any one of said metal sheets; a contact carrier provided with seven pairs of yielding contacts adapted to maintain electrical connections simultaneously with all of said plugs in holes related to the same broadcasting period of the day but with not more than two of said plugs in any one row at one time; electric clock driven means adapted to move said contact carrier parallel to said panel at such a rate as to establish said connections during periods exceeding and including the broadcasting periods corresponding to said markings; similarly driven switching means adapted, on each day of the week, to energize that pair, and only that pair, of said contacts making connections with plugs in the pair of said rows corresponding to that day of the week; similarly driven switching means adapted to energize alternatively each of the last named pair of contacts for periods closely approximating the said broadcasting periods; similarly actuated switching means adapted to break the electrical circuits through said plugs during the portion of the day not covered by said markings; and wires connected to each of said metal sheets forming part of circuits adapted, when energized, to tune in an associated radio receiving set to a particular broadcasting frequency.

5. In an automatic radio program selector, the combination of: a plurality of circuit selecting means, each adapted to be pre-set manually to pre-select any one of a plurality of tuning circuits in an associated radio receiving set; externally visible markings relating each of said circuit selecting means, when so pre-set, to a particular broadcasting period of the week and to a particular one of said tuning circuits; electric clock driven contacting means adapted to make electrical connections with each of said circuit selecting means during periods including and exceeding the broadcasting periods corresponding to said markings; and similarly driven switching means adapted to energize said contacting means only during periods approximately coinciding with the last said broadcasting periods.

6. In an automatic radio program selector, the combination of: a plurality of circuit selecting means, each adapted to be pre-set manually to pre-select any one of a plurality of tuning circuits in an associated radio receiving set; externally visible markings relating each of said circuit selecting means, when so pre-set, to a particular broadcasting period of the week and to a particular one of said tuning circuits; electric clock driven contacting means adapted to make electrical connections with each of said circuit selecting means during periods including and exceeding the broadcasting periods corresponding to said markings; and a similarly driven cam adapted to tilt a mercury switch at the beginning and end of each of said broadcasting periods to complete electrical circuits through each of said contacting means only during the periods corresponding to said markings.

7. In an automatic radio program selector, a plurality of program pre-selecting switches each correlated to a particular broadcasting period and manually operable to selectively connect with any one of a plurality of tuning circuits in an associated radio receiving set; clock controlled switching means adapted to make connections with said selecting switches during time intervals

exceeding and including the broadcasting periods to which said selecting switches are correlated; and similarly controlled switching means adapted to energize said connections only during the portions of said time intervals approximately coinciding with said broadcasting periods.

8. In an automatic radio program selector, in combination, a plurality of contact points, each in series with a circuit pre-selecting switch correlated to a particular broadcasting period, said contact points being so disposed in rows that points correlated to consecutive periods are in alternate rows; clock driven contacting means adapted to make electrical connections with each of said points during time intervals exceeding and including the broadcasting periods to which said points are correlated; and similarly driven switch means adapted to energize said contacting means alternately for time intervals closely coinciding with said broadcasting periods.

9. In an automatic radio program selector, in combination, a plurality of station pre-selecting switches each visibly related to a particular broadcasting period; clock driven switch means adapted to make electrical connections with said pre-selecting switches through time intervals exceeding and including the broadcasting periods to which said pre-selecting switches are related; and similarly driven switch means adapted to energize said connections only during said periods.

10. In an automatic radio program selector, a plurality of incomplete circuits each adapted, when completed and energized, to cause an associated radio set to be tuned to a particular frequency; a plurality of pre-selecting switching means each correlated, when pre-set, to a particular broadcasting period and operable to selectively connect with any one of said circuits, contact points forming part of the circuit through each of said pre-selecting switching means so arranged in rows that consecutive points in any one row correspond to non-consecutive broadcasting periods; contactors each adapted to make electrical connections with the said points in one of said rows; electric clock driven means adapted to move said contactors relatively to said points so as to make the said connections through time intervals exceeding and including the broadcasting periods to which said points are correlated; and similarly driven switching means adapted to energize said circuits through said points during, and only during, portions of the said time intervals approximately coinciding with the said broadcasting periods.

11. In an automatic radio program selector, a plurality of pre-selecting means each manually operable to correlate a particular broadcasting period with a particular frequency; contact points, forming part of actuating circuits through each of said pre-selecting means, so arranged in rows that consecutive points in any one row correspond to alternate broadcasting periods; contactors each adapted to make electrical connections with the said points in an assigned one of said rows; a carrier on which said contactors are mounted; a shaft provided with a continuous right and left handed spiral groove; a follower on said carrier engaging said groove; electric clockwork adapted to rotate said shaft continuously so that, while said carrier is moving in one direction, said connections are made during periods exceeding and including the broadcasting periods to which said points correspond; and a cam operated switch, actuated by said clockwork,

adapted to energize each of said contactors only during alternate broadcasting periods.

12. In an automatic radio program selector, a plurality of pre-selecting means each manually operable to correlate a particular broadcasting period with a particular frequency; contact points, forming part of actuating circuits through each of said pre-selecting means, so arranged in rows that consecutive points in any one row correspond to alternate broadcasting periods; contactors each adapted to make electrical connections with the said points in one only of said rows; a carrier on which said contactors are mounted; a shaft provided with a continuous right and left handed spiral groove; a follower on said carrier engaging said groove; electric clockwork adapted to rotate said shaft continuously so that, while said carrier is moving in one direction, said connections are made during periods exceeding and including the broadcasting periods to which said points correspond; a cam operated switch, actuated by said clockwork, adapted to energize each of said contactors only during alternate broadcasting periods; and switching means adapted to energize said contactors only during the movement of said carrier in one direction.

13. In an automatic radio program selector, a panel structure comprising a plurality of interleaved conducting and non-conducting sheets; openings through said panel structure arranged in vertically spaced groups respectively corresponding to the days of the week, the openings of each group being horizontally spaced and respectively corresponding to a daily time interval; means adapted for connecting each of said conducting sheets with a tuned circuit; contact plugs adapted for insertion into said openings for selective engagement with said conducting sheets; a carrier adapted to be horizontally traversed in a plane parallel to said panel structure means for traversing said carrier; a plurality of contactors on said carrier arranged in vertically spaced relation such that they are respectively adapted to engage individual plugs inserted in the openings of said groups for a predetermined time interval during traversal of the carrier; means for controlling the speed of travel of said carrier; and means for selectively establishing a connection between one of said contactors and an audio reproducing means.

14. In an automatic radio program selector, a panel structure comprising a plurality of interleaved conducting and non-conducting sheets; openings through said panel structure arranged in vertically spaced groups respectively corresponding to the days of the week, the openings of each group being horizontally spaced and respectively corresponding to a daily time interval; means adapted for connecting each of said conducting sheets with a tuned circuit; contact plugs adapted for insertion into said openings for selective engagement with said conducting sheets; a carrier adapted to be horizontally traversed in a plane parallel to said panel structure means for traversing said carrier; a plurality of contactors on said carrier arranged in vertically spaced relation such that they respectively successively engage the plugs of the openings of the respective groups during traversal of the carrier; means for controlling the speed of traversal of the carrier; means adapted for selectively connecting one of the contactors with the audio portion of a radio; and means for automatically controlling said last means arranged and constructed such that the contactor related to the group of openings for a

particular day of the week is connected to said audio portion on that day.

15. In an automatic radio program selector, a panel comprising interleaved sheets of conducting and non-conducting material, said panel being provided with a plurality of groups of apertures; markings relating each of the apertures of said groups to a particular broadcasting period of the day; conducting means associated with each of said conducting sheets adapted to complete electrical circuits through said sheets thereby to tune an associated radio receiving apparatus to a particular frequency; a plurality of plugs adapted to be received by said apertures for selectively contacting said conducting sheets; electrically driven timing means; switching means controlled by said timing means adapted to selectively establish a circuit through said plugs; and means controlled by said timing means for establishing a separate circuit through said switching means for each day of the week.

16. In an automatic radio program selector, a panel comprising interleaved sheets of conducting and non-conducting material, said panel being provided with a plurality of groups of apertures; markings relating each of the apertures of said groups to a particular broadcasting period of the day; conducting means associated with each of said conducting sheets adapted to complete electrical circuits through said sheets thereby to tune an associated radio receiving apparatus to a particular frequency; a plurality of plugs adapted to be received by said apertures for selectively contacting said conducting sheets; identifying marks on said plugs indicating which of said sheets the respective plugs will contact; electrically driven timing means; switching means controlled by said timing means adapted to selec-

tively establish a circuit through said plugs; and means controlled by said timing means for establishing a separate circuit through said switching means for each day of the week.

17. In an automatic radio program selector, switch means comprising a group of contacts for each day of the week; a carrier having contacts thereon adapted to engage the contacts of said groups; means for moving the carrier thereby to successively engage the carrier contacts with the group contacts; and switch means carried by the carrier for selectively energizing the contacts for one day of the week only.

GORDON R. PENNINGTON.
